DISK CUTTER WITH BEVELLED AND CONCAVE SURFACES

George E. Franck, Riverside, Ill., assignor to The Imperial Brass Manufacturing Company, Chicago, Ill., a corporation of Illinois

Application June 29, 1946, Serial No. 680,344

4 Claims. (Cl. 7—14.1)

1

The invention relates to means for forming a double flare on tubing and has as a general object to provide a new and improved means for that purpose.

A more particular object is to provide a new and improved tool which simultaneously performs two operations in the formation of a double flare on tubing.

Another object is to provide a tool which, as an incident to performing a tubing cutting-off operation, also performs a partial tubing forming operation preparing the tubing for a subsequent operation completing the making of a double flare on the tubing.

A further object is to provide a tubing cutting-off tool having a cutting wheel one face of which is formed to turn inwardly the end of the tubing being cut.

Other objects and advantages will become apparent from the following detailed description taken in connection with the accompanying drawings, in which:

Fig. 1 is a plan view of a tubing cutter embodying features of the invention adapting it for use in forming a double flare on tubing; a piece of tubing being shown in section.

Fig. 2 is a side elevational view of the cutter of Fig. 1.

Fig. 3 is an edge elevational view, somewhat enlarged over Figs. 1 and 2, of the cutting and forming wheel.

Fig. 4 is a view taken from the right in Fig. 3.

Fig. 5 is a view similar to Fig. 4 taken from the left in Fig. 3.

Fig. 6 is a very greatly enlarged radial sectional view of the cutting and forming wheel.

Fig. 7 is a view illustrating the partially formed tubing and means for performing a further operation in the flaring of the tubing.

Fig. 8 is a view similar to Fig. 7 showing the double flare completed.

While a double flare may be formed on tubing by a variety of methods, a preferred method will hereinafter be described. Similarly, while the method may be practiced with the aid of a variety of hand tools, there will be described herein a particular tool conceived to perform certain steps in the method. It is not intended, however, that the invention is to be limited to the specific tool described and shown. On the contrary, it is intended to cover all variations and alternative constructions falling within the spirit and scope of the invention as defined in the appended claims.

In systems wherein thin-walled tubing, such

as that shown at 10 in Figs. 1, 2, 7 and 8, is employed as, for example, in refrigeration systems, in the automotive and aircraft fields, etc., a piece of tubing is coupled to some device such as a coolant coil, or a carburetor, or to another piece of tubing by means commonly referred to in the trade as a fitting. In order that the tubing may be securely held in the fitting in a fluid-tight relationship as well as to be restrained against pulling out of the fitting, the end of the tubing is usually flared outwardly after one part of the fitting has been slipped over the tube. As a step in the installation of a piece of tubing, the piece of tubing is usually cut off normally to reduce it to the desired length. However, even when there is no absolute necessity to cut off the tubing for that reason, a small piece is customarily cut off anyway so as to give a new, fresh end which has not been marred, bent, etc., thereby facilitating the making of a fluid-tight coupling.

The flared portion of a tubing being the part that is clamped between the parts of the fitting, it is of course the portion of the tubing which is subjected to the greatest stresses and it has been found desirable, therefore, both from the standpoint of mechanical strength as well as from the standpoint of facility of effecting a fluid-tight seal that it is advantageous to form what is known as a double flare on the end of the tubing. By "double flare" is meant giving to the flared portion a double thickness by bending a portion of the tubing back upon itself.

Herein the method consists of four steps which conceivably may be performed sequentially in complete independence, but preferably are performed as two operations with the first operation consisting of the first and second steps performed more or less simultaneously, and the second operation consisting of the third and fourth steps also performed to a large degree simultaneously. The steps comprising this method are, first, a cutting-off of the tubing to reduce it to the desired length or to provide the unmarred end for the reasons above pointed out. It is conceivable, of course, that the tubing may be of exactly the right length and the end may be free of scratches, ridges, etc., adapting the tubing for use without a cutting-off of a portion thereof. It will readily be appreciated, therefore, that the first step may not always be imperative though it is desirable, and the omission of this step is, therefore, not to be taken as an omission of the critical and essential element of the invention. The second step is the formation, as best seen in Figs. 1 and 7, of an inward flare on the tubing. As seen in those figures,

a portion 11 at the very end of the tubing is turned inwardly in the neighborhood of 40° from its original position to adapt it for being bent or folded back upon the straight portion of the tubing on the inner side thereof. While it is conceivable, as above stated, that the steps be performed entirely independently, it is contemplated that steps one and two will be performed somewhat simultaneously. Accordingly, as an incident to and at least following in immediate succession to the cutting-off step, is the initial inturning of the portion 11.

In the third step, the portion 11 is turned further inwardly and then is folded back against the inner surfaces of the tubing 10. The fourth and final step is to flare outwardly this portion 11 of the tubing and a portion 12 (see Fig. 8) which is slightly wider than the portion 11. Here again, while it is conceivable that the portion 11 will first be completely bent back upon the tubing 10, it is preferable that this bending back of the portion 11 and the outward flaring of that portion and the portion 12 be performed in part, at least, simultaneously, for it will readily be appreciated that time and effort can be saved in that way. Herein the first and second steps of the method are disclosed as performed by a tool the particulars of construction of which were conceived to carry out the first two steps in this method, while the third and the fourth steps are carried out by the employment of a conventional flaring tool.

Referring now to Figs. 1 to 6, inclusive, there is disclosed therein a tubing-working tool devised to perform simultaneously a cutting-off and a partial forming operation, herein an inward flaring of the portion 11 of the tubing. The tool comprises a generally C-shaped body member 13. At one end, the body member 13 is shaped or carries means to form a groove extending transversely of the body for the partial reception of a piece of tubing 10 to be operated upon. Herein a pair of rollers 14 are rotatably mounted at the one end of the body member and facing inwardly so as to form between them a groove for the partial reception of a piece of tubing 10. At the other end, the body member is bored in the plane of the member for the reception slidably therein of a bar 15 of a length to project out of the bore at both ends. The bar 15 is square and the bore 50 likewise is square in transverse cross section so that the bar is held against rotation. At its inner end, the bar 15 carries means designed to perform the first and second steps of the method as the bar is fed toward a piece of tubing supported between the rollers 14 and the tool as a whole is then revolved about the tubing. While the means for performing the first and second steps of the method may be formed directly on the end of the bar 15, preferably this means is a separate, removable element. To that end, the end of the bar 15 is formed with bifurcations 16 and rotatably mounted between the bifurcations is a cutting and forming element, herein a wheel 17.

As best seen in Figs. 3 to 6, inclusive, particularly Fig. 6, the wheel has a peripheral severing edge 18. To avoid nicking of the edge 18, it is not formed as a knife edge but is given a slight width being on the order of .005 to .008 of an inch in width. This severing or cutting edge is located very near one side face or face plane of the wheel, as is clearly seen from Figs. 3 and 6, more particularly, the left side as viewed in those figures. From the edge 18 the side face 19 falls away very rapidly by means of a beveled portion 20 end, the tubing is now clamped between the bars

which forms an angle of approximately 10° to 15° with the plane of the wheel. This portion of the wheel thus performs a simple cutting-off operation. The portion of the wheel to the right of the severing edge 18, still as viewed in Fig. 6, is, however, contoured to perform the second step of the method, namely, the turning in of the portion 11 of the tubing. To that end, the surface 21 is formed as an arc at least over the portion adjacent the severing edge 18 and, herein, over the entire surface. It will be appreciated that this arc will be comparatively small, in the order of one-eighth of an inch, inasmuch as the wheel has a thickness in the order of .134 of an inch and an outside diameter of approximately nineteen thirty-seconds of an inch. The center point from which the arc is struck lies in the plane of the side face 19' of the wheel outwardly of the wheel so that a tangent to the surface 21 at the intersection with the face 19' does not exceed a right angle. Preferably, as herein, it forms a right angle. A tangent to arc 21 at the severing edge 18 forms, as best seen in Fig. 6, an angle of approximately 30° with a perpendicular to the axis of the wheel. As the severing edge 18 cuts into the tubing 10, the curved surface 21 will, of course, turn the end of the piece of tubing engaged by it inwardly progressively as the wheel 17 moves progressively inwardly of the tubing. The result, of course, is that the portion 11 of the tubing is turned inwardly, as best seen in Fig. 1, with the outer surface, particularly, forming a true radius. The wheel 17 will, of course, be made of a suitable material, such as steel hardened so as to retain a cutting or severing edge.

When, as herein, the wheel 17 has a cutting or severing peripheral edge 18 of slight width, as distinguished from a knife edge, to protect it against ready nicking, there will be formed on one of the severed pieces of tubing, usually on the piece having the inturned portion 11, a very thin burr 18' (see Fig. 1). It is, of course, not desirable that this burr remain on the piece of tubing and it is preferable, thereof, that the same be removed. Where the tubing is copper, bronze, or some other soft material, a few strokes of a file remove the burr 18' and at the same time give the piece of tubing 10 at the inturned end a squared-off end, as in Fig. 7. Such a squared-off end is desirable to assure the proper reaction of the tubing in the subsequent steps, more particularly, the inturning of the curved portion 11. Where the tubing 10 is of steel, the same procedure may be followed or the tubing may be clamped in a vise and the end having the burr 18' given a blow with a flat-faced object. This will break off the burr 18' and will also flatten or square the end of the tubing, as in Fig. 7.

On the body 13 over the outer end of the bore in which the bar 15 slides, there is rotatably mounted a knurled knob 22. This knob has such engagement with the bar 15 that upon rotation of the knob the bar is fed toward or away from rollers 14 and any piece of tubing that may be resting in the groove formed by the rollers. The mode of use of a cutting-off tool is well known to those skilled in the art.

The tubing having now been cut off to the desired length and partially formed is now ready for the remaining two operations necessary to complete the formation of a double flare. As above stated, these operations herein are performed at least partially simultaneously. To that

23 of any conventional flaring tool, one part of a fitting having customarily been slipped over the tube. The flaring tool yoke 24 is next brought into play and the screw 25 carrying the flaring cone 26 rotated so as to bring the cone into operative engagement with the end of the tubing. As the cone is forced gradually into the tubing, the portion 11 is first bent inwardly and, as the cone 26 continues to be forced into the tubing, is bent back upon the portion 12 of the tubing. At some time during this bending of the portion 11, first further inwardly and then against the portion 12 of the tubing, the portion 11 and the portion 12 are bent outwardly to form the outward flare, the bars 23 of the flaring tool being properly countersunk for that purpose. Eventually, when the cone 26 reaches the position shown in Fig. 8, the portion 11 will be lying flat against the portion 12 and both portions will be flared outwardly, as shown in Fig. 8. Thus, by two simple operations, there has been formed a piece of tubing with a double flare. The flaring tool may now be removed and the tubing is ready for completion of the coupling operation by a uniting of the parts of the coupling.

I claim as my invention:

1. An element for use in a tool for working tubing comprising a wheel having a narrow, peripheral, severing edge, a beveled face at one side of said severing edge forming a small angle with a plane perpendicular to the axis of the wheel, and a concave surface at the other side of said severing edge intersecting the adjacent side face of the wheel, the curvature of the surface being such that a tangent thereto never exceeds a right angular position with respect to a plane perpendicular to the axis of the wheel.

2. An element for use in a tool for working tubing comprising a wheel having a narrow, peripheral, severing edge, a beveled face at one side of said severing edge forming a small angle with a plane perpendicular to the axis of the wheel, and a surface at the other side of said severing edge formed as an arc with the center of curvature of the arc lying outside of the wheel

in the plane of the side of said wheel remote from the severing edge.

3. An element for use in a tool for working tubing comprising a wheel having a narrow, peripheral, severing edge, a beveled face at one side of said severing edge forming a small angle with a plane perpendicular to the axis of the wheel, and a concave surface at the other side of said severing edge intersecting the adjacent side face of the wheel, the curvature of the surface being such that a tangent thereto at the point of intersection of said surface and said adjacent side face forms substantially a right angle with respect to a plane perpendicular to the axis of the wheel.
4. An element for use in a tool for working tubing comprising a wheel having a narrow, peripheral, severing edge, a beveled face at one side of said severing edge forming a small angle with a plane perpendicular to the axis of the wheel, and a concave surface at the other side of said severing edge intersecting the adjacent side face of the wheel, the curvature of the surface being such that a tangent thereto at any point forms an angle with respect to a plane perpendicular to the axis of the wheel falling in the range 30° to 90°.

GEORGE E. FRANCK.
